SPIN DRYER HOUSING

Joel A. Elftmann, Bloomington, Minn., assignor to
Fluoroware, Inc., Chaska, Minn., a corporation of
Minnesota

Filed Feb. 7, 1968, Ser. No. 10,472

Term of patent 14 years

(Cl. D49—1)

FIG. 1 is a view in perspective of a spin dryer housing showing my new design, the side opposite that shown being substantially a mirror image thereof;

FIG. 2 is a top plan thereof; and

FIG. 3 is a side elevation thereof as seen from the left side of FIG. 1; the right side is substantially a mirror image of said left side.

The bottom, not shown, is substantially plain.

I claim:

The ornamental design for a spin dryer housing, as shown and described.
